(57) CLAIM

I claim the ornamental design for a skateboard deck, as shown and described.

DESCRIPTION

FIG. 1 is an upper perspective view of a skateboard deck showing my new design;

FIG. 2 is a left side view thereof, the right side view being a mirror image;

FIG. 3 is a top view thereof;

FIG. 4 is a bottom view thereof;

FIG. 5 is a front view thereof; and

FIG. 6 is a rear view thereof.

FIG. 7 is an upper perspective view of a modified form of a skateboard deck showing my new design;

FIG. 8 is a left side view thereof, the right side view being a mirror image;

FIG. 9 is a top view thereof;

FIG. 10 is a bottom view thereof;

FIG. 11 is a front view thereof; and,

FIG. 12 is a rear view thereof.
